PROCESS OF DISSOLVING SODIUM SILICATE.

1,138,595.

Specification of Letters Patent.

Patented May 4, 1915.

Application filed March 6, 1913. Serial No. 752,260.

To all whom it may concern:

Be it known that we, WILLIAM H. STANTON and JAMES G. VAIL, citizens of the United States, residing at Chester, in the county of Delaware and State of Pennsylvania, have invented certain new and useful Improvements in Processes of Dissolving Sodium Silicate, of which the following is a specification, reference being had

10 to the accompanying drawing.

Commercial sodium silicate, which is generally prepared by the fusion of silicious and alkaline materials in a suitable furnace, is a solid material, practically indissoluble 15 in water at ordinary temperatures and under ordinary conditions, but in order to adapt it for use in a number of the arts, it is frequently necessary to reduce it to liquid form. Considerable difficulty has been experienced 20 in commercially effecting this dissolution in the past, and it has been only possible through the employment of comparatively intricate processes, necessitating the use of expensive machinery in connection with a 25 source of power for operating the same.

The principal objects of our invention are, to provide a process or method of dissolving sodium silicate, or other like material, rapidly and economically; to provide 30 a process or method which is commercially practical on a comparatively small scale; which does not require the use of superheated steam, or of mechanical agitation, necessitating the employment of some form 35 or power, and which may be carried out practically automatically at any desired location.

Further objects of our invention are, to provide an apparatus of novel and simple 40 construction which may be employed in the carrying out of our process, and which does not necessitate the use of power; which is entirely self-contained; which may be cheaply constructed, and which may be readily 45 assembled and disassembled for cleaning or repairs; which does not require agitation in order to effect rapid and thorough dissolution of the sodium silicate, or other material, contained therein; which does not 50 require the use of flexible steam or water connections, and which may be operated economically and efficiently by unskilled labor. The invention further includes vari-

ous other novel features and objects hereinafter more definitely specified.

Briefly, our process consists in subjecting commercial sodium silicate or other material to be dissolved, to the action of any desired medium in the presence of steam or other gas, with or without the employment 60 of pressure, and at any desired temperatures.

For the purpose of carrying out our process, various forms of apparatus may be employed, one form of such apparatus being illustrated in the accompanying drawing, in which—

Figure 1 is a central vertical section thereof, and Fig. 2 is a horizontal section taken on the line 2—2 in Fig. 1.

The form of apparatus shown in the drawing consists of an outer, preferably cylindrical, casing 1, which is provided with a somewhat downwardly curved bottom 2, securely affixed to the casing 1 by means of 75 rivets 3, or in any other desired manner. This casing may be fixedly supported in a preferably upright position, in any desired manner, by means of a suitable framework or foundation, not shown. Around the 80 upper portion of the casing is preferably provided an annular collar 5 extending somewhat beyond the end of the casing and rigidly secured thereto by means of rivets 7, or in any other desired manner. The casing 85 1 may be provided with a cover 10 which fits upon the upper face of the annular collar 5, which is provided with a plurality of stud bolts 11. These bolts pass through suitable apertures in the cover 10 for the re- 90 ception of the nuts 12 to secure the cover in place.

A ring of packing 14 may be provided between the opposing faces of the cover and the annular collar, if desired, and furthermore, the annular collar may be provided with a suitable recess 15 for the purpose of more securely retaining the packing 14 in position. By tightening the nuts 12, it is thus possible to firmly seat the cover 10 100 upon the packing 14 and secure a tight joint between the cover and the annular collar. The cover 10 is preferably provided with a central circular opening or manhole which may be closed by means of the manhole 105 cover 20, which may preferably be provided

2

on its under side with a plurality of downwardly depending strengthening ribs 22, and may be removably secured in place upon the cover by a plurality of nuts 25 engaging 5 with the stud bolts 26 which are secured in the cover 10, and pass through suitable apertures in the manhole cover 20, in a manner similar to that previously described in connection with the cover 10. If desired, a ring 10 of packing 27 may similarly be inserted between the lower face of the manhole cover 20 and the upper face of the cover 10, and one or both faces may be provided, if desired, with a suitable recess 28 for more 15 securely retaining the packing in position. Of course, it will be understood that any other means for removably securing the cover 10 to the casing 1, and the manhole cover 20 to the cover 10, which will permit 20 of the ready removal of either one or both of the covers and yet retain them firmly in position while at the same time providing a steam tight joint, may be adopted if desired. Furthermore, if desired, the central 25 aperture or manhole may be entirely omitted from the cover 10 and the cover so formed as to completely close the upper end of the casing 1, in which case, of course, the manhole cover 20 and its attaching means 30 would be entirely omitted. For the purpose of affording a ready means of raising the manhole cover 20, a bracket 32 may be securely affixed to the upper side thereof, by means of bolts 33, or in any other desired 35 manner, and may be provided with a lifting eye 35 screwed into a suitable threaded aperture therein, or if desired, a lifting eye may be screwed into a suitable aperture formed directly in the manhole cover 20, or it may 40 be omitted entirely.

Within the casing 1 is preferably provided a cylindrical receptacle 38 closed at its lower end by a bottom 39, its upper end being left open. The bottom 39, which is 45 preferably made with a curvature similar to that of the bottom 2 of the casing 1, may be secured to the sides of the receptacle by means of rivets 40, or in any other desired manner, or the entire receptacle may be integrally formed of one piece of material, if desired. The receptacle 38, which is of 50 slightly smaller exterior diameter than the interior diameter of the casing 1, is suitably removably supported within the casing so as 55 to leave a small space 45 between the exterior of the receptacle 38 and all points of the interior of the casing 1, by a plurality of supports 47 lying between the exterior of the bottom 39 and the interior of the bottom 60 2, which support may be suitably affixed either to the bottom 2 or to the bottom 39, in any desired manner. Near the upper end of the receptacle 38 and on the exterior thereof are preferably provided a plurality of other 65 supports 50, suitably affixed to the recep-

tacle as by the rivets 51, which rest against the inner surface of the annular collar 5 and serve to retain the receptacle in an upright position.

The receptacle 38 is preferably provided 70 in the center of its bottom portion 39 with an outlet pipe 53 extending downwardly through a suitable aperture in the bottom 2 of the outer casing 1, which may preferably be provided with a stuffing box 54, suitably 75 attached by the rivets 55 or otherwise, having the usual gland 56 secured in place and longitudinally adjustable along the pipe 53 by means of stud bolts 57 and nuts 58 to compress the packing 59 between the inner 80 end of the gland and the stuffing box to effect a steam tight joint between the exterior of the pipe 53 and the stuffing box 55. The bottom 39 of the receptacle 38 may be provided, if desired, with a reinforcement 85 90 suitably affixed to its surface and provided with a suitably threaded aperture for the reception of the threaded end of the pipe 53 for the purpose of more firmly securing the pipe to the receptacle, or if desired, the reinforcement may be omitted if the thickness of the bottom 39 is sufficient to 95 securely hold the pipe 53.

The central aperture in the bottom 2 through which the pipe 53 passes, is preferably made of somewhat greater diameter than the exterior of the pipe, and the upper end of the aperture in the stuffing box 55 is preferably enlarged to a similar diameter for the purpose of providing an annular 100 chamber 65. A drain pipe 66 passes through the wall of the stuffing box, being suitably threaded or otherwise affixed therein and enters the chamber 65 near its bottom for the purpose to be hereinafter described. Both the drain pipe 66 and the outlet pipe 105 110 115 120 125 130 135 140 145 150 155 160 165 170 175 180 185 190 195 200 205 210 215 220 225 230 235 240 245 250 255 260 265 270 275 280 285 290 295 teenth inch in diameter, though, of course, apertures of any other suitable size may be employed.

For the purpose of introducing water or other liquid within the receptacle 38, a pipe 76 is threaded in a suitable aperture in the cover 10, this pipe being connected to some suitable source of supply and provided with a cock 77 for the purpose of controlling the flow of liquid therethrough. A short pipe or nipple 78 is threaded into the inner end of the aperture in the cover 10 and extends downwardly into the interior of the receptacle 38. A pipe 80, also provided with a cock 81 or other means, for controlling the flow of steam or other gas therein is threaded into a suitable aperture in the casing, which may be reinforced at this point by means of a plate 82 suitably secured thereto and provided with a suitable threaded aperture for the purpose of affording a more secure connection for the pipe 80.

The operation of the device is as follows: The manhole cover 20 is first removed by unscrewing the nuts 25 and lifting it off by means of the lifting eye 35. Through the aperture or manhole in the cover 10 a charge of sodium silicate or other material to be dissolved is then introduced into the interior of the receptacle 38 and supported upon the upper surface of the screen 71, the receptacle being preferably filled within a few inches of its top. Water or any other desired liquid is then introduced through the pipe 76 and the nipple 78 to the interior of the receptacle, which is filled to any desired height after which the manhole cover 20 is replaced and secured firmly in position by nuts 25, and by means of the pipe 80, steam or other gas, at any desired pressure and temperature, is introduced into the space 45 between the receptacle 38 and the casing 1. The steam or other gas immediately surrounds the receptacle and also flows over its upper edge and impinges upon its contents, quickly raising the latter to approximately its own temperature, and in a very short time effecting a complete dissolution of the solid sodium silicate or other solid material contained therein, without the necessity of any mechanical agitation either of the contents or of the apparatus. The liquid thus formed may then be drawn off by means of the pipe 53, as desired, the lower screen 70 serving to strain out any small particles of solid material which might pass through the upper screen 71, before said particles are completely dissolved. Any moisture which may form by condensation in the outer casing during the process accumulates within the annular space 65 from which it may be drawn off from time to time, by means of the pipe 66. For the purpose of preventing rapid condensation, however, the exterior of the casing 1 may be sur-

rounded by and inclosed in an asbestos or other jacket, in the well known manner now employed in covering boilers or the like, or such jacket may be entirely omitted as in the drawing.

In order to obtain the most satisfactory results in carrying out our process, it is desirable to maintain the contents of the receptacle in a substantially static or quiescent condition, and for this purpose we have found that an apparatus constructed substantially as hereinbefore described may be successfully employed. In this type of apparatus the steam or other heated gas is caused, in addition to surrounding the inner receptacle, to flow over the upper edge thereof and contact with the surface of the contained mass in which it dissolves to some extent. The temperature of the contained mass is thereby raised more rapidly near the top than near the bottom owing to the direct contact of the steam or other gas, so that the creation of convection currents and consequent circulation and agitation of the liquid is either entirely avoided or is reduced to a negligible minimum, at least until the liquid has reached a degree of concentration sufficiently great to substantially prevent reduction in the rate of solution from hydrolysis.

It will thus be seen that the dissolution of sodium silicate, or other material, in the presence of water or other liquid, may be rapidly and economically effected by the employment of steam in an apparatus such as we have described, without the necessity for any agitation of the material contained therein either directly, or by the movement of the apparatus, thus doing away completely with the necessity for the employment of power of any sort in connection with the process. Furthermore, the necessity for flexible steam or water connections is entirely done away with, as the apparatus is preferably permanently fixed in position, access being had to the interior of the receptacle for the purpose of charging the same by means of the removable manhole cover 20, it being unnecessary to remove the cover 10 with its attached water connection, except when at rare intervals it may be desired to withdraw the receptacle 38 from the casing.

It is further evident that various changes may be made in the process which we have described, without departing from the scope or spirit of our invention, and we especially do not desire to limit ourselves to the employment of any given pressure or temperature of the steam, or other gas, utilized in the process. Nor do we desire to limit ourselves in the carrying out of our process, to the employment of an apparatus such as has been described, and which forms a portion of the subject-matter of our invention, since

- any form of apparatus effective to accomplish the steps of the process may be employed, and furthermore, it will be evident that in case an apparatus of the general type which we have described, is made use of, that numerous changes in the detail and construction thereof may be made, without departing from the spirit of the invention or the scope of the appended claims.
- Having thus described our invention, what we claim and desire to protect by Letters Patent of the United States is:
1. The process of dissolving a soluble silicate or the like, which consists in treating a liquid solvent in contact with an excess of the soluble silicate with a heated gas chemically inert toward said soluble silicate while maintaining the liquid in a quiescent condition.
  2. The process of dissolving an alkaline silicate or the like, which consists in treating a liquid solvent in contact with an excess of the silicate with a heated gas chemically inert toward said silicate in such manner that circulation is minimized.
  3. The process of dissolving a soluble silicate or the like, which consists in heating a quantity of water in contact with an excess of a substantially anhydrous soluble silicate in such manner that the creation of convection currents is minimized.
  4. The process of dissolving sodium silicate or the like, which consists in heating a solvent liquid in contact with an excess of substantially anhydrous sodium silicate in such manner that circulation is minimized until the concentration of the solution has reached a point sufficient to prevent reduction in the rate of solution due to hydrolysis.
  5. The process of dissolving an alkaline silicate or the like without mechanical agitation, which consists in covering an excess of the silicate contained in a suitable receptacle with water, and then surrounding said receptacle with steam in such manner as to raise the temperature of the contents of said receptacle to approximately the temperature of said steam without the creation of convection currents.
  6. The process of dissolving an alkaline silicate or the like, which consists in heating a quantity of water in contact with an excess of substantially anhydrous silicate in such manner that circulation is minimized until the concentration of the solution has reached a point sufficient to prevent reduction in the rate of solution due to hydrolysis.
  7. The process of dissolving sodium silicate or the like, which consists in treating with steam a quantity of water in contact with an excess of substantially anhydrous sodium silicate in such manner that circulation is minimized until the concentration of the liquid has reached a point sufficient to prevent reduction in the rate of solution.
  8. The process of dissolving sodium silicate or the like, which consists in treating water in contact with an excess of sodium silicate with steam while maintaining the liquid in a quiescent condition.
- In witness whereof, I, WILLIAM H. STANTON, have hereunto set my hand and seal this 3rd day of March, A. D. 1913.

- FREDERICK A. BLOUNT,
ALEXANDER PARK.
- In witness whereof, I, JAMES G. VAIL, have hereunto set my hand and seal this 4th day of March, A. D. 1913.
- JAMES G. VAIL. [L. S.]
- Witnesses:
- GEORGE K. HELBERT,
ALEXANDER PARK.

It is hereby certified that in Letters Patent No. 1,138,595, granted May 4, 1915, upon the application of William H. Stanton and James G. Vail, of Chester, Pennsylvania, for an improvement in "Processes of Dissolving Sodium Silicate," an error appears in the printed specification requiring correction as follows: Page 4, line 50, for the words "an alkaline" read *a soluble*; and that the said Letters Patent should be read with this correction therein that the same may conform to the record of the case in the Patent Office.

Signed and sealed this 18th day of May, A. D., 1915.

[SEAL.]

R. F. WHITEHEAD,

Acting Commissioner of Patents.
